UNITED STATES PATENT OFFICE.

ALBERT T. BLACKBURN, OF JERSEY CITY, NEW JERSEY.

DESIGN FOR AN ELECTRIC CLUSTER LAMP FIXTURE.

Application filed May 19, 1927. Serial No. 22,097. Term of patent 3½ years.

To all whom it may concern:

Be it known that I, ALBERT T. BLACKBURN, a citizen of the United States, and a resident of Jersey City, in the county of Hudson and State of New Jersey, have invented a new, original, and ornamental Design for an Electric Cluster Lamp Fixture, of which the following is a specification, reference being had to the accompanying drawing, forming part thereof.

Figure 1 is a side elevation of an electric cluster lamp fixture showing my new design;

Figure 2 is an edge elevation thereof, and

Figure 3 is a top plan view of the electric cluster lamp fixture.

I claim:

The ornamental design for an electric cluster lamp fixture, as shown.

ALBERT T. BLACKBURN.
